TORQUE RESPONSIVE WASHING MACHINE

Raymond G. Olson, Niles, Ill., assignor of one-third to Kenneth T. Snow, Oak Park, Ill.

Application October 2, 1948, Serial No. 52,500

1 Claim. (Cl. 68—24)

1

This invention relates to a new and improved torque responsive washing machine.

There are numerous washing machines on the market designed to carry through an entire cycle of washing, rinsing and drying operations without anyone attending the machine. This cycle of operations requires numerous electrical and mechanical controls, making the machine quite costly and subject to numerous breakdowns. A normal cycle of washing operations or at least a cycle considered desirable by numerous washing machine companies, includes an initial washing, by a spinning of the tub at a relatively slow speed with a pre-determined quantity of hot, soapy water in the tub. The second operation or step in the cycle of operations is the draining of the hot soapy water, and the spinning of the tub at a considerably higher speed to centrifugally throw the soapy water outwardly from the tub. The next step includes the entering of rinse water and the resumption of rotation of the tub at the slower washing speed. The next successive steps include a repeating of spin drying and rinsing for several rinses. The final drying includes a spinning of the tub at a high speed to substantially drive out all of the water from the clothes or articles being washed. Very complex timing mechanisms including electrical solenoids and complicated gearing arrangements have been required to accomplish this desired cycle of washing operations.

It is a principal object of this invention to dispense with numerous electrical controls and with certain portions of the mechanical gearing, and yet accomplish the desired cycle of washing operations.

An important object of this invention is the provision of a device responsive to the torque load of the tub or washing basket to effect the driving of the tub at a low speed when the torque load is high and at a high speed when the torque load is low.

Another important object of this invention is to provide a washing machine with means therein responsive to draining of the water from the washing tub to effect a change from a slow washing speed to a high drying speed of rotation of the washing machine tub.

A still further important object of this invention is to supply a washing machine capable of completing a cycle of washing operations including washing, drying, rinsing and drying with a minimum of electrical and mechanical controls and including a torque responsive device for automatically shifting the speed of rotation

2

of the washing machine tub from a slow washing speed to a high drying speed when the wash water is drained, and conversely when the water for rinsing the wash is put into the tub, the tub automatically decreases its speed to compensate for the torque added by the water load.

Another and still further important object of this invention is to provide a fluid coupling arranged and constructed to automatically rotate a washing machine basket tub at slow speed for washing operations and to automatically increase speed of rotation of the tub to a considerably higher speed to effect a drying operation, and to automatically shift from one driving speed to the other in direct response to the water load imposed on the washing machine tub.

A still further important object of this invention is to provide a planetary gear system adapted for driving a washing machine tub in either a slow or high speed, and having means for shifting from one speed to the other speed responsive to the torque load of the washing machine tub.

Other and further important objects of this invention will become apparent from the disclosures in the following specification, and accompanying drawings.

In the drawings:

Figure 1 is a perspective view of a washing machine of the type employing the torque responsive mechanism of this invention.

Figure 2 is a rear elevational view of the washing machine as shown in Figure 1.

Figure 3 is a sectional view taken on the line 3—3 of Figure 2.

Figure 4 is a wiring diagram partially in schematic form showing the electrical mechanisms in the washing machine of this invention.

Figure 5 is a sectional detail view taken on the line 5—5 of Figure 2.

Figure 6 is a view similar to that of Figure 5 partially in section of a modified form of torque responsive device.

Figure 7 is an enlarged detail view partially in section of a portion of the device as shown in Figure 3.

Figure 8 is a front elevational view of the device as shown in Figure 7.

As shown in the drawings:

The reference numeral 10 indicates generally a supporting structure or washing machine housing, having a base 11, a front panel 12, a top 13, a door 14 hinged at 15 on the front panel 12 and having a handle latch means 16 for locking the door in a closed position.

As best shown in Figure 2 the housing or supporting structure 10 is equipped with a cradle-like carrying structure 17 having upwardly and inwardly inclined legs 18 and concave adjoining member 19 for supporting the inner housing 20 of the washing machine. The housing or tub 20 is a watertight compartment and access to this tub is gained through the front door 14 through which the clothes to be washed are inserted and removed. The tub 20 is cylindrical in shape and carries an inner perforate tub or basket 21 journally mounted therewithin for driven rotation. The cylindrical tub 20 is fixedly mounted with respect to the housing or supporting structure 10 on a generally horizontal axis and has no movement with respect thereto. The basket 21 is also cylindrical in shape and has perforations 22 over the full annular surface thereof. The bracket 21 rotates within the tub 20 and by so doing sufficiently agitates the clothes therewithin to effect a washing thereof. The rigid fastening of the tub 20 to the housing 10 is accomplished by riveting or other fastening means at 23 on the front panel 12 of the cabinet. Legs 24 and 24a bolted to the bottom of the cabinet at 24b space the tub a fixed distance above the base of the supporting structure and further support the tub.

A source of power in the form of an electric motor 25 is mounted on the base 11 within the housing 10. The motor 25 is mounted rigidly with the supporting structure and is disposed in a manner in which the driving shaft extends in a direction from the front to the rear of the cabinet 10. This motor driving shaft is designated by the numeral 26 and carries a V-belt pulley or the like 27 which by means of a V-belt 28 imparts rotational drive to a V-belt pulley 29 carried on the shaft 30. The shaft 30 is journally mounted on a bracket 31 bolted at 32 to the tub supporting leg 24. A second V-belt pulley 33 is mounted and fixed on the shaft 30 and carries a V-belt 34 extending upwardly to a large V-belt pulley 35 as best shown in Figure 5. The pulley 35 is mounted on and attached to a shaft 36 which is supported at one end in an aperture 37 in a cross support or brace 38 extending between the sides 39 and 40 of the cabinet or supporting structure 10. The aperture 37 acts as a bearing support for the shaft 36. An end thrust-nut 42 holds the pulley in position on the shaft 36. The shaft 36 is thus rotatably driven at a constant high rate of speed from the motor 25.

A pin 43 passes through the shaft 36 and through a hub 44 of a turbine-like rotor or vane member 45. A plurality of plates or vanes are circumferentially spaced around the periphery of the rotor 45. The rotor 45 is thus driven at a constant high rate of speed from the motor 25. The turbine member 45 forms a part of a fluid coupling 46 having a fluid tight disc shaped housing 47 with complementary shell-like housing portions 48 and 49 bolted together around outwardly extending peripheral flanges 48a and 49a at 50. Inwardly projecting non-driven blades or bucket members 51 are mounted rigidly with respect to the portion 49 of the housing of the fluid coupling 46 at circumferentially spaced intervals therearound. A fixed amount of fluid within the housing 46 tends to impart drive from the opposing vanes of the rotating turbine member 45 to the stationary baffles or vanes 51 and cause the housing 47 to rotate therewith. The inner end of the shaft 36 is journalled for free rotation within a hub 52 of the housing portion 48. This

hub 52 extends laterally and is itself journally carried for rotation within an opening 53 in the rear end of the tub 20. The opening has press fitted therein a circular sleeve bearing 53a. A reduced diameter end portion of the hub 52 forms a shoulder 54 which permits a flush reception of the sleeve bearing 53a. This flush engagement of the bearing and the hub is conducive to effect the necessary liquid tight seal that must exist at the tub opening 53. A lateral extension 55 of the hub 52 is threadedly attached to a stub shaft 56 projecting rearwardly from the inner perforate washing basket 21. The stub shaft 56 is carried on a reinforcing bracket 57 which is in turn riveted or otherwise attached to the basket 21 at 58. It will thus be seen that as the motor 25 is driven, the basket 21 is also rotatably driven through the fluid coupling 46 in the manner just described.

The stationary tub 20 is provided with a sump 59 at the bottom thereof and is equipped with a drain 60. A pump 61 is directly attached to the drain 60 and acts to pull the water, either washing or rinse water, from the tub 20 out through the sump for discharge from the washing machine. The pump 61 is of the rotor type and is driven by the motor 25 through a V-pulley 62 mounted on the other end of the shaft 26. A V-belt 63 joins the V-pulley 62 with a V-pulley 64 which is mounted on a shaft 65 of the rotor pump 61. Inasmuch as it is not desired to run the pump 61 continuously, means is provided for effecting operation only at the times when it is desired to drain the washing machine tub 20 of its water content. Included in the means for driving the pump at only predetermined desired intervals is an electric solenoid 66 energized by cycle timing means to effect driving engagement between the motor shaft 26 and the V-pulley 62. The details of this mechanism are more fully shown in Figures 7 and 8. The outer end of the shaft 26 is splined as indicated at 67. This spline slidingly receives an internally splined clutch member 68. The pulley 62 is journalled for free rotation on and over the shaft 26. A clutch member 69 is integrally associated with the pulley 62 and rotates therewith. A collar 70 mounted on the shaft 26 prevents endwise movement of the pulley 62 in that direction. The clutch members 68 and 69 as shown in Figure 7 are in cooperative driving engagement and in this position the motor shaft 26 directly drives the clutch member 68 through the spline 67 and thus causes rotational drive of the cooperative clutch member 69 and thus also the V-pulley 62. The clutch member 68 is provided with an integral annular groove 71 for engagement by a shifter fork 72 which is suspended from the bottom of the stationary tub 20 by means of a hinge 73. A piston 74 operatively reciprocated by the solenoid 66 is pivotally attached at 75 to the shifting fork 72 and thus it will be seen that when the solenoid is not energized the piston 74 and thus the shifting fork will be extended and the clutch member 68 will be moved laterally away from the clutch member 69 causing disengagement of the driving means between the motor shaft 26 and the V-pulley 62. In this latter described position the pump 61 is not driven and the water is not withdrawn from the tub 20. This type of clutch is merely one of many that may be employed for this job. A mixing valve 76 is carried on the supporting structure at the rear of the cylindrical tub 20. The mixing valve is fed by a hot water inlet 77 and a cold water inlet 78 directly from house

water lines. An outlet 79 is provided from the mixing valve 76 and is adapted to discharge at 80 on the top of the washing tub 20 as indicated in Figure 2. The mixing valve 76 is controlled by solenoids 76a and 76b which act to admit hot and cold water respectively when they are electrically actuated.

As best shown in Figure 4 the cycle of washing operations is controlled by electrical means which will now be described. The wiring diagram of Figure 4 shows the imposing of line voltage at 81 to the circuit. A cam 82 is mounted on a shaft 83 and upon rotation in a clockwise direction causes a switch 84 to be closed and the circuit to the motor 25 completed causing operation of the motor. Means (not shown) is provided between the motor and the shaft 83 to effect continuous slow rotation of the shaft 83 so that one revolution thereof denotes a full washing cycle. When the cam 82 resumes its position as shown in Figure 4 the motor 25 will be stopped. An alternate means of driving the shaft 83 would be by a separate synchronous motor such as used in electric clocks. A second cam 85 is mounted on the shaft 83 and rotates therewith adjacent the cam 82. The peripheral contour of the cam 85 is arranged and constructed to carry out all the other operations in the full cycle of washing operations. It should be noted that any number of cams may be employed to effect the operation of any part or parts of the washing cycle.

The cam 85 moves in a clockwise direction as indicated by the arrow 86 and similar to the rotation of the cam 82. The first segment of the cam 85 designated by the numeral 87 causes an upward swinging of the contact arm 88 completing the circuit between the line voltage and the mixing valve solenoid 76a for energizing the solenoid and thus admits hot water to the washing machine tub 20. In order to accomplish this result a contact point 89 of the arm 88 moves upwardly into engagement with a contact 90 of the hinged arm 91.

The second segment 92 of the cam 85 causes continued upward movement of the contact arm 88 thus forcing the hinged arm 91 upwardly so that its integral contact 93 will engage a contact 94 on an arm 95 which joins the line voltage with the mixing valve solenoid 76b to effect entering and mixing of cold water with the hot water. The filling of the tub with wash or rinse water is thus completed in the first two segments 87 and 92 of the cam 85. Variations in flow of water are controlled by a metering means 120 which consists of a bleed tube 121 from the mixing valve 76 to meter a certain proportion of incoming water for filling a tube 122. A float (not shown) in the tube 122 has a vertically disposed rod 123 for controlling the flow of water from the mixing valve to the washing tub and thus when the water in the tube 122 reaches a predetermined level the water in the tub has also reached the desired washing or rinsing level and the float acts through its rod 123 to turn the flow of water off regardless of whether the cam 85 calls for continued filling. A conduit 122a joins the bottom of the tube 122 to the tub 20 and thus when the tub is drained the tube 122 is also drained permitting the tube to act in a succeeding washing.

Continued rotation of the cam 85 moves it to the third segment thereof designated by the numeral 93a. This cam segment 93a is coincident with the washing or rinsing operation of this washing machine. The segment 93a is so shaped as to place the contact arm 88 in the position as

indicated in Figure 4 wherein neither hot nor cold water is running, nor is the pump 61 drawing water from the tub.

Subsequent to the washing period it is desired to remove the water from the tub 20 and this is accomplished in the fourth segment 94a of the cam 85 during which time the contact arm 88 is permitted to drop with the result that the contact point 89a integral with the bottom of the arm 88 engages the contact 96 on the arm 97 thus completing the electrical circuit from the line voltage to the pump solenoid 66 and as previously described, actuation of the solenoid 66 effects driving rotation of the V-pulley 62 by the motor 25. The pump 61 then draws the water from the tub 20 through the sump 59 and thereupon discharges it through the pipe 98 indicated in both of Figures 2 and 3.

Following the discharge of water from the tub 20 it is the next cycle of washing operation to spin the clothes wash in the perforate rotatable basket 21 to effect removal, by centrifugal force, of the water therein. This last shown segment of washing operations is indicated by the numeral 99 on the cam 85. In this position the status of the several elements is similar to that of the washing operation wherein water is neither put in nor taken out. It should be understood that the pump 66 continues to run through the spin dry to remove the water from the machine as it is drawn from the clothes.

Upon completion of a full revolution of the shaft 83 the motor 25 turns off and thus the cycle of operations is finished. It is to be further understood that this cycle of operations may be more or less enlarged depending upon whether or not rinsing is desired. The cam 85 may be made with the proper contour to effect any number of washings, rinsings, and spin dryings in any one cycle of operations. However, in the present instance in view of the fact that the invention relates only to the torque responsive means in association with a washing machine it is deemed not necessary to make the cycle of operations more complex.

In all of the present day washing machines complicated gearing is a necessity for changing the speed of rotation of the basket tub 21 from a slow washing speed during the washing cycle to a high spin drying speed for the centrifugal extrusion of the water from the clothes. In addition to the complex gearing, complicated mechanisms for effecting a shifting of that gearing from one speed to another is necessary. As previously stated it is an important object of this invention to provide an automatic changing of the speed of the washing basket 21 from a slow washing speed to a high drying speed merely upon draining of the water from the tub 20 within which the perforate wash basket is rotatably mounted. As best shown in Figure 2, the washing level of the water within the tub 20 is indicated by the numeral 100. This level of water remains in the tub during the full movement of the cam 85 through its segment 93a. The resistance or torque load of the basket 21 is considerably greater with the water in the tub 20 than when the tub has no water and it is on this principle that the washing machine of this invention operates. The vanes or plates of the fluid coupling 46 are sufficiently spaced apart in a lateral direction so that upon an application of great torque load such as occasioned by the water in the tub 20 to the level indicated by the numeral 100 the plates 51 and thus the housing 47 con-

tinuously slip and are never brought up to the speed of rotation of the driven vanes 45. When, however, the torque load is reduced by the draining of the water from the tub 20 the plates 51 are easily brought up to the speed of rotation of the moving vanes 45 thus causing direct and full speed drive of the perforate basket 21.

The fluid coupling 46 is therefore a natural torque responsive device which may be arranged and constructed with proper spacing to provide a slow speed on one torque load and a considerably higher speed on a reduced torque load. The shifting of one speed of rotation of the washing basket 21 to another speed of rotation is automatically accomplished by means responsive solely to the level of the water within the washing tub 20. When water is in the tub, whether it be wash or rinse water, it is desirable to rotate the tub at a relatively slow speed in order to be effective in washing or rinsing of clothes therein, and conversely when there is no water in the tub it is desirable to spin dry the clothes at a high speed of rotation. By means of the fluid coupling torque responsive device the perforate basket tub 21 is driven at the desirable speed automatically in any position of the cycle thereof.

As best shown in Figure 6 a modified form of torque responsive means is shown. In lieu of the fluid coupling a planetary gearing is employed which is adapted upon change in torque load to effect a change in output speed. A sun gear 101 is journally mounted on the shaft 36 and is driven by the shaft through the means of a pin 102 extending radially outwardly through an inclined or helically extending slot 103 in an annular surface of a hub 104 of the sun gear. The planet carrier 105 is also journalled on the shaft 36. Longitudinally operable clutch means 106 in the form of a coil spring is positioned between the sun gear and the planet carrier within annular grooves 107 and 108 in the sun gear and planet carrier respectively and positioned adjacent the shaft 36. The planet carrier 105 carries planet gears 109 which are engaged with the sun gear 101. The gears 109 are mounted on short shaft members 110 which in turn are mounted in a spider portion of the planet carrier 105. An outer ring gear 111 is concentric with the sun gear 101 and is in geared engagement with the planets 109. A supporting structure 112 carries the outer ring gear 111 on a journal support mounted over the shaft 36 and between the cross or brace member 38. The structure 112 is provided with a sleeve-like extension 113 which is directly mounted on the shaft 36 for separate rotation. A one-way brake 114 is positioned over the sleeve hub 113 of the supporting structure 112 and within a circular aperture 115 within the cross brace member 38. The brace member 38 is stationary with the supporting structure 10 and thus the one-way brake permits rotation of the ring gear carrying structure 112 in one direction but bars rotation in the other direction.

In operation as the shaft 36 is driven, drive is imparted to the sun gear 101 through the shaft pin 102 and helical or spiral slot 103 in the sun gear. A spring 116 normally urges the sun gear longitudinally of the shaft 36 and toward the planet carrier 105. In this position the spring clutch 106 is adapted to impart drive directly from the sun gear to the planet carrier 105. This planet carrier is provided with a laterally extending hub or shaft portion 117 which is journalled within the bearing 53a in the opening 53 of the tub 20 and is attached to the inner perforate

basket member 21 by means of bolts 118 extending through a flange or spider member 119 of the hub 117. It will thus be seen that the basket 21 is capable of being driven through the planetary gearing directly from the sun gear to the planet carrier to the basket. However, this drive is only accomplished when the torque load is sufficiently light to permit the sun gear to remain in closely adjacent contact with the planet carrier. When the torque load is increased by applying water to the tub 20 the sun gear 101 tends to back up against the action of the spring 116 causing the pin 102 to move to the inner end of the helical shaped slot 103. In this position the clutch 106 has released its engagement of the sun gear and planet carrier and the driving of the planet carrier is accomplished indirectly through the planet gears 109. It is obvious that upon an application of a greater torque load the speed of rotation of the output is considerably less than the direct speed of rotation obtained on a light torque load. When the sun gear is directly engaged with the planet carrier 105 through the clutch 106 it is essential that the outer ring gear 111 be permitted free rotation in the same direction so that the rotational drive from the shaft 36 to the basket 21 may be accomplished with the entire planetary gearing rotating as a single unit. However, when the planet carrier is driven by the planet gears 109 it is essential that the outer ring gear 111 which tends to rotate in the opposite direction be held stationary in order that the rotational power may not be dissipated therethrough. The one-way brake 114 is arranged and constructed so that it provides the necessary reactance for the planet carrier when that carrier is driven by the planet gears and also permits free rotation of the ring gear when the basket drive is one to one.

In operation of the washing machine with any type of torque responsive device it should be understood that when the motor is initially turned on the washing machine with a load of clothes and no water will go into a fast spin. This is advantageous as it tends to fluff the clothes and evenly distribute them in the tub before the tub is filled with wash water. Bunching and matting of clothes in the wash tub is thus minimized. As water is fed to the washing machine tub the basket automatically reduces its speed of rotation. Balance of the wash basket is properly maintained. Should there exist an excessive unbalancing of the basket whether with or without water the torque load is sufficiently increased so the basket cannot go into a fast spin. There is thus much less danger of damage being caused to the machine by such an unbalancing as in ordinary washing machines because of this automatic operation.

It will thus be seen that the washing machine of this invention whether employing the fluid coupling or the planetary transmission will effectively operate in response to the torque load dependent on water in the washing machine tub to either drive the tub at a slow washing speed or a fast spin drying speed.

Numerous details of construction may be varied over a wide range without departing from the principles disclosed herein and I therefore do not propose limiting the patent granted hereon otherwise than as necessitated by the appended claim.

What is claimed is:

A washing machine comprising a supporting framework, a cylindrical water-tight tub fixed to

said supporting framework and disposed on a generally horizontal axis, a cylindrically shaped perforated basket slightly smaller than said tub and journally mounted on a generally horizontal axis for rotation within said tub, a fluid coupling including a fluid-tight disc shaped housing having circumferentially spaced stationary plates projecting inwardly within said housing, said housing attached to said basket, a rotor having circumferentially spaced plates fastened thereto, said rotor disposed within said disc shaped housing and the plates thereof opposing the inwardly projecting plates of said housing and spaced a substantial distance apart, a fixed quantity of fluid within said disc shaped housing, means for rotating said rotor at a substantially constant high speed, means for supplying water to said tub, said tub having a water drain, means for controlling the opening and closing of said water drain, means for operating said means to cause drainage of water from said tub, cycle timer means arranged and constructed to actuate the means for operating said means, whereby when the tub contains water the substantial axial spacing of the rotor and housing of the fluid

5 coupling will act to transmit only a portion of the substantially constant high speed of rotation of said rotor to said perforated basket because of the great torque load, and whereby after the tub is drained of its water through operation of said cycle timer actuating said means for operating the means controlling the opening and closing of said drain whereby the perforated basket with its lesser torque load is rotated by the fluid coupling at the same high rate of speed of rotation as the coupling rotor.

RAYMOND G. OLSON.
